UNITED STATES PATENT OFFICE.

ALBERT SCHMIDT, OF FLINT, MICHIGAN, ASSIGNOR TO CHAMPION IGNITION COMPANY, OF FLINT, MICHIGAN, A CORPORATION OF MICHIGAN.

SPARK-PLUG.

1,355,274.

Specification of Letters Patent. Patented Oct. 12, 1920.

Application filed November 22, 1917. Serial No. 203,295.

To all whom it may concern:

Be it known that I, ALBERT SCHMIDT, a citizen of the Republic of France, residing at Flint, in the county of Genesee and State 5 of Michigan, have invented certain new and useful Improvements in Spark-Plugs, of which the following is a specification, reference being had therein to the accompanying drawings.

10 The invention relates to spark-plugs and has more particular reference to a construction designed for use in high-speed motors. In the present state of the art great difficulty has been experienced in connection 15 with the using of spark-plugs on high-speed motors from one or the other of two opposed conditions; first, there is the difficulty of pre-ignition occurring when the plug is too hot either through residual flame in the plug 20 chamber or the heating of some part of the surface to ignition temperature or from other causes not known. The other difficulty is where the plug is too cool and short circuiting occurs through carbon deposits on 25 the insulating surface. Most attempts that have been made to cure the first difficulty will introduce the second, and vice versa.

It is the object of the present invention to avoid both difficulties, which is accomplished, first, by maintaining all the large 30 masses of the plug and the space which may contain burning gas at a temperature below the ignition point; second, by maintaining a zone in the insulating surface exposed to 35 high temperature sufficient to burn off or prevent the formation of carbon deposits, and which nevertheless will lose its temperature during the introduction of the explosive gas so as to prevent pre-ignition. This 40 I have accomplished by the construction as hereinafter set forth.

In the drawings:

Figure 1 is a longitudinal section through a plug embodying my invention;

45 Fig. 2 is a cross-section on line 2—2 Fig. 1. A is the outer metallic casing of the plug, B the insulated electrode and C the insulator therefor. This insulator, instead of projecting into the explosion chamber, to a 50 point adjacent to the spark gap, is arranged in the outer portion of the casing which is comparatively cool. As shown, the insulator is in a portion of the outer casing A beyond the nipple A' which screws into 55 the water-jacket of the engine, and the point

of contact with the electrode B as well as with the outer casing is still further removed. This results in a skirt-like inward projection of the insulator separated both from the electrode and the outer casing, and the inner edge of the skirt is tapered to a thin edge D. Adjacent to this thin edge the space between the insulator and the outer casing is contracted to form an annular narrow slot E through which the gases are 60 compelled to travel at high velocity. In rear of this point the skirt is increased in thickness to enlarge the mass thereof for the absorption and conduction away of heat imparted thereto, as indicated at F. The 65 electrode B is preferably formed of relatively large cross-section increasing from the sparking point toward the point of bearing upon the insulator, as indicated at G. H is a bushing for securing the insulator 70 within the casing A, which bushing is shown as permanently engaging an enlargement I of the insulator and also as sealing against a shoulder J on the casing.

With the construction as thus far described, when the plug is in operation the compressed gases will be forced through the restricted slot E into the larger chamber K which is between the skirt and the outer casing. The high velocity of movement is 85 sufficient to sweep clear any deposit which might occur at the point of contraction. The knife-edge D is exposed to the combustion heat and on account of its relatively small mass will attain a temperature too 90 high for the deposit of carbon thereon, but as soon as combustion ceases the larger mass in the skirt in rear of the edge D will absorb the heat. The effect is therefore to insure cooling of the knife-edge before explosive gases are compressed thereagainst 95 and the temperature of the skirt and casing A in the portions thereof adjacent to the chamber K is too low to permit the continuance of flame therein. Thus insulation 100 is maintained and pre-ignition is guarded against.

In the construction illustrated the plug is provided with an outer insulator member L seated upon the bushing H and having a 105 wrapping of mica or other insulating material M for bridging the joint between the outer and inner insulators. A heat-radiating member N is also placed on the shank of the electrode beyond the outer insulator 110

L, and a clamping nut O engaging a threaded end portion P of the shank is provided for securing the electrical connections.

What I claim as my invention is:

5. 1. In a spark-plug, the combination with a casing and an electrode, of an insulator contacting with said electrode and casing at a point beyond the range of intense heat and provided with an inwardly-extending skirt terminating in an annular thin edge which is exposed to the more intense heat, the space between said skirt and casing having a restriction adjacent to said thin edge to increase the velocity of gases passing therethrough.
10. 2. In a spark-plug, the combination with a casing and an electrode therein, of an insulator for said electrode having a portion contacting therewith and with the outer casing at a point beyond the range of intense

heat, said insulator also having an inwardly-extending skirt portion terminating in a thin edge which is exposed to the more intense heat, and a shoulder on said casing forming an annular restricted passage adjacent to said thin edge with a larger chamber beyond the same, for the purpose described.

15. 3. In a spark plug, the combination with a casing, of a bushing engageable with said casing, an electrode, an insulator arranged between said electrode and bushing, a second insulator surrounding a portion of said electrode and seated upon said bushing, and insulating material between said electrode and insulators and bridging the joint between the latter.

2

In testimony whereof I affix my signature.

ALBERT SCHMIDT.
